CLAIM

The ornamental design for a medical bed, as shown and described.

DESCRIPTION

FIG. 1 is a perspective view of a medical bed in accordance with our design;

FIG. 2 is a front elevation view thereof;

FIG. 3 is a rear elevation view thereof;

FIG. 4 is a left elevation view thereof;

FIG. 5 is a right elevation view thereof; and,

FIG. 6 is a top plan view thereof.

The broken lines in the drawings are employed to show unclaimed portions of the medical bed, and form no part of the claimed design.

1 Claim, 6 Drawing Sheets
